MACHINE FOR FORMING RINGS FROM A FLEXIBLE STRIP

Maurice M. Balsam and Henry M. Balsam, New York, N. Y., assignors to M. M. Balsam, Inc., New York, N. Y.

Application June 21, 1947, Serial No. 756,310

18 Claims. (Cl. 69—1)

1

Our invention relates to machines for forming rings from a flexible strip.

It is an object of our invention to provide a machine for forming flexible rings from a strip of flexible material in a substantially automatic way.

It is a further object of our present invention to provide machines of the above type which are simple in construction and can be operated by anybody without the necessity of any particular skill.

It is another object of our present invention to provide machines of the above type which can be adjusted so as to produce rings of various sizes and/or of various materials.

With the above objects in view, a machine in accordance with our present invention comprises in combination a series of elements, namely continuously operating driving means, loop forming means intermittently operated by these driving means and constructed so as to form during each its intermittent operation periods a closed loop from a short portion of a flexible strip, connecting means also intermittently operated by the above mentioned driving means and constructed so as to connect during each of its intermittent operation periods the ends of the closed loop formed by the above defined loop forming means, and finally, feeding means also intermittently operated by the above driving means and constructed so as to feed during each of its intermittent operation periods a short portion of the above mentioned flexible strip to the loop forming means.

It is preferable to combine with the loop forming means described above separate adjusting means for adjusting and varying the size of the loops formed by the loop forming means.

Furthermore, it is advisable to provide in a machine of the above type also cutting means intermittently operated by the driving means and constructed so as to cut off during each of its intermittent operation periods the short strip portion fed by the feeding means to the loop forming means.

In accordance with a preferred embodiment of our invention, the loop forming means comprise a stationary loop forming member and movable loop forming means intermittently operated by driving means described above and constructed so as to bend during each of its intermittent operation periods a short strip portion around the stationary loop forming member so as to form a closed loop.

In order to adjust the size of the finished rings,

2

it is not only necessary to provide, as set forth above, adjusting means for adjusting the size of the loop forming means, e. g. the size of the stationary loop forming member, but it is also necessary to provide adjusting means associated with the above described feeding means for adjusting and varying the length of the short strip portions fed by the feeding means to the loop forming means.

10. In order to properly position the short strip portions between the stationary loop forming member and the movable loop forming means after each variation of the length of the short strip portions, it is advisable to provide means 15 for adjusting the distance between the feeding and cutting means on the one hand, and the loop forming means on the other hand. These adjusting means preferably consist of a common movable support carrying said feeding and cutting means and constructed so as to be movable in direction towards and away from said stationary loop forming means enabling adjustment of the distance between said feeding means and said cutting means on the one hand, and said stationary loop forming member and said movable loop forming means on the other hand so as to properly position said short strip portions between said stationary loop forming member and said movable loop forming means after each adjustment of the length of said short strip portions fed by said feeding means between said stationary loop forming member and said movable loop forming means.

Finally, it is advisable to provide also removing means intermittently operated by the above described driving means and constructed so as to remove during each of its intermittent operation periods a finished ring of flexible strip material from the stationary loop forming member described above.

40. The novel features which we consider as characteristic for our invention are set forth in particular in the appended claims. The invention itself, however, both as to its construction and its method of operation, together with additional objects and advantages thereof, will be best understood from the following description of specific embodiments when read in connection with the accompanying drawings, in which:

50. Fig. 1 is a perspective view of a machine built in accordance with the present invention;
 Fig. 2 is a fragmentary front elevational view of the machine, seen in direction of arrow 2 of Fig. 1;
 Fig. 3 is an elevational view similar to Fig. 2,

55. Fig. 4 is a fragmentary front elevational view of the machine, seen in direction of arrow 4 of Fig. 1;

but showing the machine in loop-forming position;

Fig. 4 is a fragmentary sectional view of the machine, taken along line 4—4 of Fig. 2;

Fig. 5 is a sectional view similar to Fig. 4, but showing the knife in cutting position;

Fig. 6 is a perspective view of one side of the machine, seen in direction of arrow 6 of Fig. 1;

Fig. 7 is a perspective view of the opposite side of the machine, seen in direction of arrow 7 of Fig. 1;

Fig. 8 is a sectional view of the machine, taken along line 8—8 of Fig. 7; and

Fig. 9 is an enlarged view of a ring formed by the machine.

In carrying the invention into effect in one of the embodiments which has been selected for illustration in the accompanying drawings and for description in this specification, and referring now particularly to Fig. 1, there is provided a table 10 supported by a post 11. A frame structure indicated by reference numeral 15 is mounted on the table 10 and a bracket 12 is secured to the side of the table; this bracket supports the spool 13 carrying a continuous leather strip 14 from which are formed the leather rings 96 shown in Fig. 9.

A motor 16 is supported by said post 11 at the lower end thereof and carries a driving pulley 17 for driving, by means of a belt 18, a driven pulley 19. This pulley 19 is mounted on the frame 15 by means of the shaft 21. This shaft 21 extends through a speed reduction box 22 containing a reduction gearing (not shown in detail) and carries on its other end a hand wheel 23 for manual operation of the machine.

A driving shaft 24 is turnably supported by the frame structure 11 and is arranged above the table 10 normal to the direction of shaft 21. This shaft 24 is driven by the reduction gearing arranged in the gear box 22 and runs at a reduced speed compared to the speed of shaft 21.

Three cams 26, 27, and 28 are mounted on the driving shaft 24 and rotate together therewith when the latter revolves.

As shown in Fig. 8, the cam 26 drives a cam following lever 29 which is pivoted at 31 to the frame structure 15 and is connected near its other end by means of pivot 33 to a pushing rod 32. A coiled tension spring 34 is connected to this lever 29 near the pivot 33 and is capable of returning the lever 29 to its rest position (indicated in dot and dash lines in Fig. 8), when the lever is released by the cam 26.

The pushing rod 32 is pivotally connected at 36 to an adjustable feeding mechanism designed in the drawings with reference numeral 37. This feeding mechanism is composed of a U-shaped member 38 swingably mounted on the feed shaft 39 and carries a centrally located screw threaded spindle 41 which is provided at its upper end with a knurled knob 42 for manually rotating this spindle. The sliding block 43 is provided with a screw hole and is carried by the screw threaded spindle 41. As clearly shown in Fig. 8, this sliding block is pivoted by means of pivot 36 to the pushing rod 32.

A spring pressed pawl 44 is swingably pivoted to the U-shaped member 38 and engages the teeth of a ratchet wheel 46 which is rigidly mounted on the feed shaft 39.

The angular oscillating movement of the lever 29 is determined by the shape of the cam 26; this in turn determines the oscillating movement of the pivot 33. Likewise, the pushing rod 32 is

intermittently oscillated by the lever 29 once during every rotation of the driving shaft 24, resulting in oscillating turning movement of member 38 and pawl 44. The extent of this turning movement depends upon and is adjusted by the sliding block 43, the position of which is manually adjusted by the spindle 41 and knob 42. Thus, by adjustment of knob 42, it is possible to adjust the extent of the angular oscillating movement of pawl 44 carried by the member 38 and the angular movement of the ratchet wheel 46 since the same is driven in one direction by the pawl 44. During the return movement, the pawl 44 idles on the teeth of the ratchet wheel 46, and this ratchet wheel remains in standstill during such return movement of the pawl. Thus, the oscillating movement of the lever 29 is transformed into a unidirectional intermittent turning movement of controlled extent of the ratchet wheel 46 and of feed shaft 39 carrying this wheel.

The feed shaft 39 extends rearwardly to a hand wheel 47 and extends forwardly over two flexible couplings 48 to a pinion 49, as clearly shown in Figs. 2 and 7. This pinion 49 is in mesh with another pinion 51 which in turn meshes with a gear 52 of equal size as pinion 51 and located underneath the same. Each of the pinions 51 and 52 is coaxially mounted with a roller, namely the pinion 51 driving the roller 53 and the pinion 52 driving the roller 54. These rollers 53 and 54 are arranged adjacent to each other and transport the leather strip 14 when they are revolved by means of the gear train 49, 51 and 52 described above.

The gear 51 and roller 53 driven by it are mounted on a lever 56 which is pivoted at 57 to the common horizontally slidable support 61 slidable carried by table 10. The position of the lever 56 and of roller 53 and gear 51 carried by the same may be adjusted by means of a screw threaded spindle 58 carrying a knob 59 for manual operation.

The lever 56 as well as both rollers 53 and 54 and both gears 51 and 52 are mounted on the horizontally slidable support 61 described above. This support is movable on the table 10 by means of a knob 63 mounted at the rear end of spindle 62 extending through a screw threaded hole in the stationary bracket 64 for adjustment of the length of the loop to be formed from the leather strip 14. After the member 61 has been brought into the desired position by means of the knob 63 and spindle 62, the same may be fixed in that position by screw 66 passing through a hole in the table 10.

A loop forming and cutting mechanism indicated by reference numeral 65 is provided at the front of the table 10 and comprises a carriage 67 which oscillates up and down once during every revolution of the driving shaft 24. This mechanism is actuated by the oscillating cam 27, as shown in Fig. 6, namely by means of a vertical rod 68 which is pressed downwardly by the oscillating cam 27 against the power of the coiled spring 69. This rod 68 imparts an oscillating turning movement to one end of the lever 71 which is pivoted to the stationary bracket 72. The other end of this lever 71 is pivoted to the carriage 67 and causes the same to raise when the rod 68 is pressed downwardly by the cam 27, and to descend by its own weight when the spring 69 moves the rod 68 upwardly.

Above the carriage 67 there is arranged a pair of semi-cylindrical loop forming members 73 and 74 which are arranged opposite one another.

The upper member 73 is stationarily mounted on the frame structure 15 and the lower member 74 is movable in vertical direction in order to adjust the distance therefrom from the stationary loop forming member 73. This movable loop forming member 74 is carried by a lever 76 which is pivoted by means of pivot 77 to the frame structure 15 and movable up and down by means of an adjustment spindle carrying a knurled knob 79. The distance between these loop forming members determines the size of the loop formed of the leather strip 14.

The slideable carriage 67 which is arranged below the loop forming members 73 and 74 carries a vertically slideable abutment member 81 which has a cylindrical segmental top surface 82, and a spring 84 permanently forcing the member 81 in upward direction. Two hook-shaped loop forming members 83 are juxtaposed and each hook is located at one side of said abutment member 81 and pivoted by means of pivot 84 to the carriage 67. Each of these hook members 83 is furthermore provided with a guiding pin 86, and these pins are arranged so as to slide along the parallel edges of a stationary guide member 87. The hook members are pressed by springs 88 mounted on the carriage 67 towards each other, whereby the pins 86 are permanently pressed against the guide 87, as clearly shown in Fig. 2.

When lever 61 raises the carriage 67, the abutment member 81 will press a portion of the leather strip 14 against the curved underside of the loop forming member 74. While the carriage 67 proceeds in its upward movement, the abutment member 81 remains in its abutting position pressing the member 74 and the leather strip therebetween; this is due to action of the spring 84 located under the abutment member 81 as described above in detail. During such upward movement of the carriage, the pins 86 of the hook members 83 will slide along the edges of the stationary guide 87 until they reach the cylindrical top 87 thereof and are pressed towards each other by the springs 88.

During this movement of the carriage, but after the abutment member 81 has engaged the leather strip 14, this strip will be cut by the knife 89—which will be described farther below in detail—and the hook members 83 will bend the leather strip 14 around the loop forming members 73 and 74 until, in the final upper position of the stroke of the carriage, the leather strip forms a complete loop around these members.

A stapling device 92 is located above the upper stationary loop forming member 73 and is movable upward and downward by a crank (not shown) driven by the driving shaft 24; this stapling device completes one cycle during every full turn of the driving shaft 24.

As best shown in Fig. 3, when the hook-shaped loop forming members 83 have completed the loop around the stationary loop forming members 73 and 74, the stapling device 92 is lowered and drives a staple 93 through the juxtaposed ends 94 of the loop. The hook-shaped members 83 are so curved on their top that when they are in their uppermost closest position shown in Fig. 3 their points are spaced for a distance sufficient to permit the passage therebetween of the staple 93.

A removing device, called also ejector 97, is pivoted by a stationary pivot 98 to the frame structure 15 and carries a cam follower 99 which reaches into the path of the pin 101 carried by

the cam 28. A spring 102 is connected to the ejector 97 so as to hold the same normally in inactive position. This ejector 97 has an end portion which conforms in shape to the curvature of the upper loop forming member 73; this end portion is normally located in inactive position to the rear of the member 73. After the ring 96 has been formed, the pin 101 strikes the cam follower 99 and thereby actuates the ejector 97 so as to remove the finished ring from the loop forming members 73 and 74 and to eject it in frontward direction.

As the leather strip 14 is transported by the rollers 53 and 54, it passes through a gate member 103 formed between two parallel bars having aligned and smooth surfaces. This gate member is also carried by the common horizontally slideable support 61 described above in detail.

The knife 89 has a cutting edge 104 which, when the knife is moved upwardly, glides along the front face of the gate 103 and cuts off the strip 14. This knife 89 is carried by a tiltable lever 106 that is pivoted to a stationary pivot 107 mounted on the above described support 61. It should be stressed that the knife 89 is movable between two extreme angular positions which are limited by means of an arcuate slot formed in the lever 106 that engages the pin 108 which is also mounted on the support 61.

30 A bracket 109 is secured to the side of the carriage 67 and carries an actuating arm 111 pivoted thereto. When the carriage 67 is moved upwardly, the actuating arm 111 forces the free end of the lever 106 in an upward direction until the knife 89 has reached its extreme upper position and has completed its cutting operation. In that position the curved top of the actuating element 111 forces the same sidewardly against the resistance of a spring pressed pin 112 so as to avoid damage between the pin 108 and the edges of the slot in the lever 106.

When the carriage moves downwardly, the lever 106 is returned to its normal inactive position by means of a coiled spring.

45 Our above described machine operates as follows:

The motor 16 continuously drives the driving pulley 17 and this driving pulley, in turn, continuously drives by means of the belt 18 the driven pulley 19. Pulley 19, in turn, rotates by means of the shaft 21 and the reduction gearing arranged in the gear box 22 the driving shaft 24 and the cams 26, 27, and 28 mounted on this shaft.

55 Rotation of the cam 26 causes the flexible strip 14 to be fed between the semi-cylindrical loop forming member 74 and the upper end of the abutment member 82.

The moment the strip is in proper position between these two members, rotation of cam 27 causes the carriage 67 to move upwardly pressing by means of the abutment member 82 the strip 14 against the member 74.

60 Simultaneously, the actuating arm 111 pivoted to the carriage by means of bracket 109 operates the knife 89 as described above and shown in Figs. 4 and 5, resulting in cutting off of strip 14.

The cut off strip portion is then bent during further upward movement of the carriage 67 as clearly shown in Fig. 3 and described above.

65 The moment the carriage reaches its final operating position shown in Fig. 3, rotation of shaft 24 operates the stapler mechanism 92 moving the same downward and stapling the two ends of the short loop-shaped strip portion together by

means of staple 93 so as to form the finished ring 96 shown in Fig. 9.

This finished ring 96 is then ejected and removed from the loop forming members 73 and 74 by means of the removing mechanism shown in Fig. 2. This removing mechanism is automatically actuated by rotation of cam 28 as described above in detail.

All of above operations occur during and are caused by one revolution of the driving shaft 24. When this shaft 24 returns into its initial position, the machine is ready for production of the next leather ring.

In order to adjust the size of the leather or similar ring produced by our new machine, the following three manual adjustments have to be carried out:

First, it is necessary to adjust by means of a knob 42 the length of the short strip portions fed by the rollers 53 and 54. Then, as second step, the distance of the loop forming members 73 and 74 is adjusted by means of knob 79 so that the combined outer circumference of these members is equal to the length of the short strip portions fed by the rollers 53 and 54. Finally, the position of the support 61 is adjusted by knob 63 so as to properly center the short strip portions fed by the rollers 53 and 54 around the stationary loop forming members 73 and 74.

It will be understood that each of the elements described above, or two or more together, may also find a useful application in other types of ring forming machines, differing from the types described above.

While we have illustrated and described the invention as embodied in machines for forming leather and similar rings, we do not intend to be limited to the details shown, since various modifications and structural changes may be made without departing in any way from the spirit of our invention.

Without further analysis, the foregoing will so fully reveal the gist of our invention that others can by applying current knowledge readily adapt it for various applications without omitting features that, from the standpoint of prior art, fairly constitute essential characteristics of the generic or specific aspects of this invention, and, therefore, such adaptations should and are intended to be comprehended within the meaning and range of equivalence of the following claims.

What we claim as new and desire to secure by Letters Patent is:

1. In a machine for forming rings from a flexible strip, in combination, driving means; loop forming means intermittently operated by said driving means and constructed so as to form during each of said intermittent operation periods a closed loop from a short portion of said flexible strip; adjusting means associated with said loop forming means for adjusting and varying the size of the loops formed by said loop forming means; connection applying means intermittently operated by said driving means and constructed so as to connect during each of said intermittent operation periods the ends of the closed loop formed by said loop forming means; and feeding means intermittently operated by said driving means and constructed so as to feed during each of said intermittent operation periods a short portion of said flexible strip to said loop forming means.

2. In a machine for forming rings from a flexible strip, in combination, driving means; loop forming means intermittently operated by said

driving means and constructed so as to form during each of said intermittent operation periods a closed loop from a short portion of said flexible strip; connection applying means intermittently operated by said driving means and constructed so as to connect during each of said intermittent operation periods the ends of the closed loop formed by said loop forming means; feeding means intermittently operated by said driving means and constructed so as to feed during each of said intermittent operation periods a short portion of said flexible strip to said loop forming means; and cutting means intermittently operated by said driving means and constructed so as to cut off during each of said intermittent operation periods said short portion of said flexible strip fed by said feeding means to said loop forming means.

3. In a machine for forming rings from a flexible strip, in combination, driving means; loop forming means intermittently operated by said driving means and constructed so as to form during each of said intermittent operation periods a closed loop from a short portion of said flexible strip; adjusting means associated with said loop forming means for adjusting and varying the size of the loops formed by said loop forming means; connection applying means intermittently operated by said driving means and constructed so as to connect during each of said intermittent operation periods the ends of the closed loop formed by said loop forming means; feeding means intermittently operated by said driving means and constructed so as to feed during each of said intermittent operation periods a short portion of said flexible strip to said loop forming means; and cutting means intermittently operated by said driving means and constructed so as to cut off during each of said intermittent operation periods said short portion of said flexible strip fed by said feeding means to said loop forming means.

4. In a machine for forming rings from a flexible strip, in combination, driving means; a stationary loop forming member; movable loop forming means intermittently operated by said driving means and constructed so as to bend during each of said intermittent operation periods a short portion of said flexible strip around said stationary loop forming member so as to form a closed loop; connection applying means intermittently operated by said driving means and constructed so as to connect during each of said intermittent operation periods the ends of said closed loop formed by said movable loop forming means around said stationary loop forming member; and feeding means intermittently operated by said driving means and constructed so as to feed during each of said intermittent operation periods a short portion of said flexible strip between said stationary loop forming member and said movable loop forming means.

5. In a machine for forming rings from a flexible strip, in combination, driving means; loop forming means intermittently operated by said driving means and constructed so as to form during each of said intermittent operation periods a closed loop from a short portion of said flexible strip; connection applying means intermittently operated by said driving means and constructed so as to connect during each of said intermittent operation periods the ends of the closed loop formed by said loop forming means; feeding means intermittently operated by said driving means and constructed so as to feed during each of said intermittent operation periods a short portion of said flexible strip to said loop forming means.

11

tween said stationary loop forming member and said movable loop forming means after each adjustment of the length of said short strip portions fed by said feeding means between said stationary loop forming member and said movable loop forming means.

11. In a machine for forming rings from a flexible strip, in combination, driving means; a stationary loop forming member; movable loop forming means intermittently operated by said driving means and constructed so as to bend during each of said intermittent operation periods a short portion of said flexible strip around said stationary loop forming member so as to form a closed loop; adjusting means associated with said stationary loop forming member for adjusting and varying the size of the loops formed by said movable loop forming means around said stationary loop forming member; connection applying means intermittently operated by said driving means and constructed so as to connect during each of said intermittent operation periods the ends of said closed loop formed by said movable loop forming means around said stationary loop forming member; feeding means intermittently operated by said driving means and constructed so as to feed during each of said intermittent operation periods a short portion of said flexible strip between said stationary loop forming member and said movable loop forming means; adjusting means associated with said feeding means for adjusting and varying the length of said short strip portions fed by said feeding means between said stationary loop forming member and said movable loop forming means; cutting means intermittently operated by said driving means and constructed so as to cut off during each of said intermittent operation periods said short portion of said flexible strip fed by said feeding means between said stationary loop forming member and said movable loop forming means; and a common movable support carrying said feeding means and said cutting means and constructed so as to be movable in direction towards and away from said stationary loop forming member and said movable loop forming means enabling adjustment of the distance between said feeding means and said cutting means on the one hand and said stationary loop forming member and said movable loop forming means on the other hand so as to properly position said short strip portions between said stationary loop forming member and said movable loop forming means after each adjustment of the length of said short strip portion fed by said feeding means between said stationary loop forming member and said movable loop forming means.

12. In a machine for forming rings from a flexible strip, in combination, driving means; a stationary loop forming member; movable loop forming means intermittently operated by said driving means and including two loop forming hook members moved by said driving means during each of said intermittent operation periods towards and around said stationary loop forming member so as to bend during each of said intermittent operation periods a short portion of said flexible strip around said stationary loop forming member and to form a closed loop out of the same; connection applying means intermittently operated by said driving means and constructed so as to connect during each of said intermittent operation periods the ends of said closed loop formed by said movable loop forming means; and feeding means intermittently operated by said driving means and constructed so as to feed during each of said intermittent operation periods a short portion of said flexible strip between said stationary loop forming member and said movable loop forming means; ad-

12

means around said stationary loop forming member; and feeding means intermittently operated by said driving means and constructed so as to feed during each of said intermittent operation periods a short portion of said flexible strip between said stationary loop forming member and said movable loop forming means.

13. In a machine for forming rings from a flexible strip, in combination, driving means; a stationary loop forming member; movable loop forming means intermittently operated by said driving means and including two loop forming hook members moved by said driving means during each of said intermittent operation periods towards and around said stationary loop forming member so as to bend during each of said intermittent operation periods a short portion of said flexible strip around said stationary loop forming member and to form a closed loop out of the same; adjusting means associated with said stationary loop forming member for adjusting and varying the size of the loops formed by said movable loop forming means around said stationary loop forming member; connection applying means intermittently operated by said driving means and constructed so as to connect during each of said intermittent operation periods the ends of said closed loop formed by said movable loop forming means around said stationary loop forming member; feeding means intermittently operated by said driving means and constructed so as to feed during each of said intermittent operation periods a short portion of said flexible strip between said stationary loop forming member and said movable loop forming means; and cutting means intermittently operated by said driving means and constructed so as to cut off during each of said intermittent operation periods said short portion of said flexible strip fed by said feeding means between said stationary loop forming member and said movable loop forming means.

14. In a machine for forming rings from a flexible strip, in combination, driving means; a stationary loop forming member; movable loop forming means intermittently operated by said driving means and including two loop forming hook members moved by said driving means during each of said intermittent operation periods towards and around said stationary loop forming member so as to bend during each of said intermittent operation periods a short portion of said flexible strip around said stationary loop forming member and to form a closed loop out of the same; adjusting means associated with said stationary loop forming member for adjusting and varying the size of the loops formed by said movable loop forming means around said stationary loop forming member; connection applying means intermittently operated by said driving means and constructed so as to connect during each of said intermittent operation periods the ends of said closed loop formed by said movable loop forming means around said stationary loop forming member; feeding means intermittently operated by said driving means and constructed so as to feed during each of said intermittent operation periods a short portion of said flexible strip between said stationary loop forming member and said movable loop forming means; ad-

justing means associated with said feeding means for adjusting and varying the length of said short strip portions fed by said feeding means between said stationary loop forming member and said movable loop forming means; cutting means intermittently operated by said driving means and constructed so as to cut off during each of said intermittent operation periods said short portion of said flexible strip fed by said feeding means between said stationary loop forming member and said movable loop forming means; and means for adjusting the distance between said feeding means and said cutting means on the one hand and said stationary loop forming member and said movable loop forming means on the other hand so as to properly position said short strip portions between said stationary loop forming member and said movable loop forming means after each adjustment of the length of said short strip portions fed by said feeding means between said stationary loop forming member and said movable loop forming means.

15. In a machine for forming rings from a flexible strip, in combination, driving means; a stationary loop forming member; movable loop forming means intermittently operated by said driving means and including two loop forming hook members moved by said driving means during each of said intermittent operation periods towards and around said stationary loop forming member so as to bend during each of said intermittent operation periods a short portion of said flexible strip around said stationary loop forming member and to form a closed loop out of the same; adjusting means associated with said stationary loop forming member for adjusting and varying the size of the loops formed by said movable loop forming means around said stationary loop forming member; connection applying means intermittently operated by said driving means and constructed so as to connect during each of said intermittent operation periods the ends of said closed loop formed by said movable loop forming means around said stationary loop forming member; feeding means intermittently operated by said driving means and constructed so as to feed during each of said intermittent operation periods a short portion of said flexible strip between said stationary loop forming member and said movable loop forming means; adjusting means associated with said feeding means for adjusting and varying the length of said short strip portions fed by said feeding means between said stationary loop forming member and said movable loop forming means; cutting means intermittently operated by said driving means and constructed so as to cut off during each of said intermittent operation periods said short portion of said flexible strip fed by said feeding means between said stationary loop forming member and said movable loop forming means; and a common movable support carrying said feeding means and said cutting means and constructed so as to be movable in direction towards and away from said stationary loop forming member and said movable loop forming means enabling adjustment of the distance between said feeding means and said cutting means on the one hand and said stationary loop forming member and said movable loop forming means on the other hand so as to properly position said short strip portions between said stationary loop forming member and said movable loop forming means after each adjustment of the length of said short strip por-

tion fed by said feeding means between said stationary loop forming member and said movable loop forming means.

16. In a machine for forming rings from a flexible strip, in combination, driving means; a stationary loop forming member; movable loop forming means intermittently operated by said driving means and constructed so as to bend during each of said intermittent operation periods a short portion of said flexible strip around said stationary loop forming member so as to form a closed loop; connection applying means intermittently operated by said driving means and constructed so as to connect during each of said intermittent operation periods the ends of said closed loop formed by said movable loop forming means around said stationary loop forming member; feeding means intermittently operated by said driving means and constructed so as to feed during each of said intermittent operation periods a short portion of said flexible strip between said stationary loop forming member and said movable loop forming means; and removing means intermittently operated by said driving means and constructed so as to remove during each of said intermittent operation periods a finished ring of said flexible strip from said stationary loop forming member.

17. In a machine for forming rings from a flexible strip, in combination, driving means; a stationary loop forming member; movable loop forming means intermittently operated by said driving means and including two loop forming hook members moved by said driving means during each of said intermittent operation periods towards and around said stationary loop forming member so as to bend during each of said intermittent operation periods a short portion of said flexible strip around said stationary loop forming member and to form a closed loop out of the same; adjusting means associated with said stationary loop forming member for adjusting and varying the size of the loops formed by said movable loop forming means around said stationary loop forming member; connection applying means intermittently operated by said driving means and constructed so as to connect during each of said intermittent operation periods the ends of said closed loop formed by said movable loop forming means around said stationary loop forming member; feeding means intermittently operated by said driving means and constructed so as to feed during each of said intermittent operation periods a short portion of said flexible strip between said stationary loop forming member and said movable loop forming means; adjusting means associated with said feeding means for adjusting and varying the length of said short strip portions fed by said feeding means between said stationary loop forming member and said movable loop forming means; cutting means intermittently operated by said driving means and constructed so as to cut off during each of said intermittent operation periods said short portion of said flexible strip fed by said feeding means between said stationary loop forming member and said movable loop forming means; and removing means intermittently operated by said driving means and constructed so as to remove during each of said intermittent operation periods a finished ring of said flexible strip from said stationary loop forming member.

18. In a machine for forming rings from a flexible strip, in combination, driving means; a

15

stationary loop forming member; movable loop forming means intermittently operated by said driving means and including two loop forming hook members moved by said driving means during each of said intermittent operation periods towards and around said stationary loop forming member so as to bend during each of said intermittent operation periods a short portion of said flexible strip around said stationary loop forming member and to form a closed loop out of the same; adjusting means associated with said stationary loop forming member for adjusting and varying the size of the loops formed by said movable loop forming means around said stationary loop forming member; connection applying means intermittently operated by said driving means and constructed so as to connect during each of said intermittent operation periods the ends of said closed loop formed by said movable loop forming means around said stationary loop forming member; feeding means intermittently operated by said driving means and constructed so as to feed during each of said intermittent operation periods a short portion of said flexible strip between said stationary loop forming member and said movable loop forming means; adjusting means associated with said feeding means for adjusting and varying the length of said short strip portions fed by said feeding means between said stationary loop forming member and said movable loop forming means; cutting means intermittently operated by said driving means and constructed so as to cut off during each of said intermittent operation periods said short portion of said flexible strip

fed by said feeding means between said stationary loop forming member and said movable loop forming means; a common movable support carrying said feeding means and said cutting means and constructed so as to be movable in direction towards and away from said stationary loop forming member and said movable loop forming means enabling adjustment of the distance between said feeding means and said cutting means on the one hand and said stationary loop forming member and said movable loop forming means on the other hand so as to properly position said short strip portions between said stationary loop forming member and said movable loop forming means after each adjustment of the length of said short strip portion fed by said feeding means between said stationary loop forming member and said movable loop forming means; and removing means intermittently operated by said driving means and constructed so as to remove during each of said intermittent operation periods a finished ring of said flexible strip from said stationary loop forming member.
